UNITED STATES PATENT OFFICE

LELAND S. ROSENER, OF SAN FRANCISCO, CALIFORNIA, ASSIGNOR TO THE PARAFFINE COMPANIES, INC., OF SAN FRANCISCO, CALIFORNIA, A CORPORATION OF DELAWARE

PRINTING-PRESS ATTACHMENT

Application filed January 9, 1929. Serial No. 331,314.

My invention relates to printing presses, and particularly to presses for applying the designs to felt base or linoleum rugs or other floor coverings.

5 An object of my invention is to provide a means of reducing the time during which a press is out of service for cleaning.

Another object of my invention is to facilitate the cleaning of the inking mechanism of 10 a printing press.

Still another object of my invention is to provide a means by which a press of the character described may more speedily and conveniently be changed from one design or color 15 scheme to another.

My invention possesses other objects and valuable features, some of which will be set forth in the following description of my invention which is illustrated in the drawings 20 forming part of the specification. It is to be understood that I do not limit myself to the showing made by the said description and drawings, as I may adopt varying forms of my invention within the scope of the claims.

25 The presses used for printing felt base floor coverings are large and bulky, and represent a large capital investment, not only in themselves but in auxiliary equipment, buildings, etc. Obviously if this investment 30 is to pay a proper return it must be kept in operation during as large a part of the working day as possible. One of the most serious causes of interruption is the necessity for periodically cleaning the mechanism which sup-

35 plies the colors to the printing blocks. These inkers, which are mounted to roll on a track on the press bed, must be scraped and washed with benzine, and as they are cumbersome and heavy it has been the practice in the past 40 to perform this operation with the inker in place on the press.

Broadly, my invention comprises an auxiliary track arranged to be connected with the track on the press bed, and means associated 45 with this auxiliary track permitting the interchange in position on the tracks of the press inker and a second inker carried by the auxiliary track. By means of this arrangement a clean inker may be substituted for the one on the press with a negligible interrupt-

tion of operation. The foul inker may then be cleaned at leisure and prepared for instantaneous substitution when the second inker requires cleaning.

Referring to the drawings:

55 Figure 1 is a side elevation of the press and the auxiliary track. Because of the length of the apparatus, portions of the apparatus have been broken away and the figure has been divided in two parts on the line 1—1, Figure 1^a showing the press itself, while Figure 1^b shows the auxiliary track and its associated equipment.

Figure 2 is a plan view of the press, the superstructure and portions of the platen being cut away to show the mechanism more clearly.

65 Figure 3 is a side elevation, on a larger scale, of the switching device used in the auxiliary track.

70 Figure 4 is a fragmentary sectional view, taken on the line 4—4 of Figure 1^a, and showing, on a larger scale, the end of the inker and its track and the method of feeding the rug base thru the press.

75 For the purpose of detailed description, I have shown a preferred form of my invention as used in combination with a printing press of known type, comprising a frame 6 mounted on the wheels 7 to run on the rails 8, which are laid perpendicular to the longitudinal axis of the frame. The press can be moved along these rails by the operation of the motor 9 and gear train 11, which meshes with the pinion 12 on the longitudinal shaft 80 13 carrying the wheels 7. The pinion also meshes with a rack 14, laid parallel to the rails, to provide a positive drive. By this mechanism the press may be moved into alignment with any of the drying racks (not shown) which are provided for the printed 85 rugs.

90 Since the press is of known construction, it need merely be pointed out here that the motor 16, operating thru suitable gearing, drives the reciprocating printing heads 17, (of which, to conserve space, but one is shown) and the Geneva movement 18 which operates the endless conveyor chains 19. These chains carry pins 21, and the base fabric 22, passing 95 100

from a roll 23, is pressed onto these pins by the roller 24, the chains carrying it intermittently along the press platen 26.

The motor 16 also actuates a pair of reciprocating mechanisms 27, 27, each of which drives an arm 28 which is coupled by a link 29 with the inkers. Dash pots 30, connected with the arms 28, control and steady the motion of the inkers.

10 Each of the latter comprises a trough shaped ink pot 31 which extends transversely of the press platen and is carried on flanged wheels 32 engaging a track 33 formed in the edge of the platen. Adjacent the track is a 15 rack 34. A gear 36 meshes with the rack, and, thru an intermediate gear 37, drives a gear 38 fixed to a shaft 39 which is journaled in the ends of the ink pot and which carries the inking roller 41. It will be seen that when the 20 reciprocating mechanisms move the ink pots the rollers are turned to carry the ink to the faces of the printing blocks 42, carried by the printing heads 17. Scrapers 43 rest against the rollers to remove excess ink, and ensure a 25 uniform coating on the printing blocks. The inkers move together as a train, each being connected with the next by a link 44. It will be realized that the inkers are heavy and that the ink they contain is easily spilled. It is, 30 therefore, impractical to lift them from the track, even with the crane 46 with which the press is provided.

Arranged so that the press may be moved into alinement with it, is the auxiliary track. 35 This may be conveniently constructed of angle bars 51 carried on angle cross ties 52 which are mounted on vertical struts 53. The track preferably comprises three principal sections, each of sufficient length to accommodate the complete train of inkers. Two of 40 these sections are arranged as a superposed pair in the same vertical plane, one, indicated by the general reference character 54, being slightly below the level of the press track, 45 and the other, indicated by the reference character 56, slightly above this plane. The third section 57 may be connected as an extension of either of these tracks by means of switch rails 58, each having dowels 59 in its lower 50 flange for engaging holes 61 in the cross ties on which it rests. The ends of the vertical flange of the switch rails are beveled to form a smooth joint with the rails 51. When it is desired to reverse the switch the rails are 55 lifted from their seats, turned end for end and interchanged. A similar switch allows either track 54 or 56 to be connected with the press.

The connection with the press is made by 60 a horizontal pair of removable rails 62 which are held by dowels 63, similar to those on the switch rails, on the cross tie 64 at one end and on a similar tie or angle 66 secured to the press at the other.

65 When it is desired to clean the inkers, the

press is moved into alinement with the auxiliary track, the rails 62 are placed in position, and the switches are set to the lower track 54. The links 29 are disconnected and the train of inkers is rolled onto the lower track, after which the switches are reversed and a clean set of inkers, held ready on the upper track, is moved onto the press. Operation of the press may then be immediately resumed, while the foul inkers are moved onto the storage track 57 and cleaned at the tank 67 there provided for the purpose. After cleaning, the inkers are refilled and moved to the upper track in readiness for the next change. The clean inkers may, if desired, be filled in accordance with an entirely different color scheme, and a change in the design of the rug effected in little more time than is required for cleaning.

I claim:

1. In combination with a printing press having a track and an inker movable on said track, an auxiliary track arranged for connection with said press track, and means associated with said auxiliary track permitting the interchange in position on said tracks of the press inker and a second inker carried on said auxiliary track.

2. In combination with a printing press having a track and an inker movable on said track, an auxiliary track arranged for connection with said press track, and switching means associated with said auxiliary track permitting the interchange in position on said tracks of the press inker and a second inker carried on said auxiliary track.

3. In combination with a printing press having a track and an inker movable on said track, a pair of auxiliary tracks arranged for connection with said press tracks, and a switch connecting said press track alternately to each of said auxiliary tracks.

4. In combination with a printing press having a track and an inker movable on said track, a pair of superposed auxiliary tracks arranged for connection with said press track, and a switch connecting said press track alternately to each of said auxiliary tracks.

5. In combination with a printing press having a track and a plurality of inking devices movable upon said track, means connecting said inking devices in a train, an auxiliary track adjacent said press track, and means associated with said auxiliary track permitting the interchange in position on said tracks of said train and a similar train carried on said auxiliary track.

6. In combination with a printing press having a track and an inker movable on said track, a pair of superposed auxiliary tracks arranged for connection with said press track, and a switch comprising a removable track section and means for alining said sec-

tion alternatively with each of said auxiliary tracks.

7. In combination with a printing press having a track and an inker movable on said track, an auxiliary track above the level of the press track, an auxiliary track below the level of the press track, a storage track, and switches for connecting said press track and said storage track alternatively with said upper and lower auxiliary tracks.

8. An attachment for a printing press having a track and an inker movable on said track, comprising an auxiliary track arranged for connection with the press track, and means associated with said auxiliary track permitting the interchange in position on said tracks of the press inker and a second inker carried on said auxiliary track.

9. An attachment for a printing press having a track and an inker movable on said track, comprising a pair of auxiliary tracks arranged for connection with said press track, and a switch connecting said press track alternatively to each of said auxiliary tracks.

10. An attachment for a printing press having a track and an inker movable on said track, comprising a pair of superposed auxiliary tracks arranged for connection with said press track, and a switch comprising a removable track section and means for alining said section alternatively with each of said auxiliary tracks.

In testimony whereof, I have hereunto set my hand.

LELAND S. ROSENER.
